CLAIM

The ornamental design for a coffee machine, as shown and described.

DESCRIPTION

1. Coffee machine
2. Coffee machine
- 1.1: is an axonometric view of the first embodiment of a coffee machine showing my new design;
- 1.2: is a front elevation view thereof;
- 1.3: is a right elevation view thereof;
- 1.4: is a back elevation view thereof;
- 1.5: is a left elevation view thereof;
- 1.6: is a top elevation view thereof; and
- 1.7: is a bottom elevation view thereof.
- 2.1: is an axonometric view of the second embodiment of the coffee machine of 1.1
- 2.2: is a front elevation view thereof;
- 2.3: is a right elevation view thereof;
- 2.4: is a back elevation view thereof;
- 2.5: is a left elevation view thereof;
- 2.6: is a top elevation view thereof; and
- 2.7: is a bottom elevation view thereof.

The broken lines in FIGS. 1.7 and 2.7 depict portions of the coffee machine that form no part of the claimed design.

1 Claim, 14 Drawing Sheets
